UNITED STATES PATENT OFFICE.

EDWIN MCCIESNEY, OF HERMAN, MINNESOTA.

DESIGN FOR A TOOTHPICK.

SPECIFICATION forming part of Design No. 24,691, dated September 24, 1895.

Application filed May 14, 1895. Serial No. 549,319. Term of patent 14 years.

To all whom it may concern:

Be it known that I, EDWIN MCCIESNEY, a citizen of the United States, residing at Herman, in the county of Grant and State of Minnesota, have invented a new and original Design for Toothpicks, of which the following is a specification.

This invention relates to a new and original design for toothpicks; and it has for its object to provide a design of this character that shall be both useful and ornamental.

The leading feature of the design resides in an elongated concave-convex body provided with lanceolar ends and opposite intermediate semicylindrically-shaped side extensions bounded at their edges by sigmoidal lines running from point to point of the body.

In the drawings, Figure 1 is a perspective view of a toothpick embodying the herein-described design. Fig. 2 is a central trans-

verse sectional view of the same, and Fig. 3 a side elevation.

Referring to the drawings, the numeral 1 designates an elongated concavo-convex toothpick-body. The concavo-convex body 1 is provided with lanceolar ends 2 and opposite intermediate semicylindrically-shaped side extensions 3, bounded at their edges by the sigmoidal lines 4, running from point to point of the body.

What I claim is—

The design for a tooth-pick herein shown and described.

In testimony that I claim the foregoing as my own I have hereto affixed my signature in the presence of two witnesses.

EDWIN MCCIESNEY.
